UNITED STATES PATENT OFFICE

2,002,814

PRINTING-PRESS

Charles W. Harrold, Cleveland, Ohio, assignor to
 Harris-Seybold-Fotter Company, Cleveland,
 Ohio, a corporation of Delaware

Application January 14, 1932, Serial No. 586,521

16 Claims. (Cl. 101—136)

My invention relates more particularly to multicolor rotary off-set printing-presses embodying improvements by which the colors on the sheets or web may be readily equalized to the length of the plates in each of the colors used in the press caused by stretching of the paper and swelling due to the moisture imparted from the dampening mechanisms.

Heretofore the practice has been to correct the unequal lengths of the print from one color to another by over-packing or under-packing the plate cylinders in the several units, since reducing the diameters of the plate-cylinders lengthens the print, while increasing the cylinder diameter shortens the print. In either case, however, the actual print is usually slightly longer than the design on the plate so that due allowance must be made in laying out the work. Such changes in the diameters of the plate-cylinders are also objectionable in that they disturb the proper working relation with the coating rubber-cylinder in off-set printing by causing a pull or slip between the surface of the two coating cylinders so that the design on the plate will wear off.

The objects of my invention are, among other things, to provide a new and improved multicolor off-set press with the impression-cylinders in the several printing couples ground in graduated relation to one another with varying diameters so that this stretching of the paper may be taken care of in equalizing the length of the print to that of the plate to print the several colors in accurate registry, since the reduction of the diameter of the impression-cylinders shortens the print, while increasing same will lengthen the print.

According to my invention as shown in the accompanying drawing in a four-color off-set press, the impression-cylinder of the fourth and last unit is of standard size, while the diameters of the remaining three impression-cylinders are progressively diminished backwardly through the press to the first unit, the impression-cylinder in such first unit being the smallest in diameter. In such a lay-out the several colors will print in exact registry, and the length of the print will be that of the plates on various plate cylinders. Furthermore the graduated impression-cylinders of the several units make it unnecessary to over-pack or under-pack any of the plate-cylinders to any appreciable extent, and the desired equalization of the lengths of the several prints on the paper is attained.

In the drawing, Fig. 1 is a diagrammatic side-

elevation of a multi-color rotary off-set printing press embodying my improvements centered about the varying diameters of the four impression-cylinders ground in graduated relation;

Fig. 2 is a plan view of a sheet printed with the gripper edge along the left margin and the back edges on the right margin showing an overlapped relation due to the varying lengths of the print in the different colors; and

Fig. 3 is a plan view similar to Fig. 2, but showing the back edges of the prints, in several colors, in registering superposition when the four impression-cylinders are ground to varying diameters according to my improvements.

Similar letters and numerals refer to similar parts throughout the several figures.

Referring to Fig. 1 showing a multi-color press embodying four printing-couples or units A, B, C and D which are all built alike and are arranged in series, each unit comprises the plate-cylinder 4, the rubber or blanket cylinder 5, and impression-cylinder 6. Superposed on the plate-cylinders 4 are the usual inkers 7 with the dampening mechanisms 8 on right-hand lower side of the plate-cylinders 4. The feed-rollers 9 and 10 take the sheet S from the roller feed-table 11, and deliver such sheet to the grippers 12 on the impression-cylinder 6 of the first unit A in the usual way. The gears of the cylinders 4, 5 and 6 in each unit rotate in unison, but the surface speeds of the cylinders are slightly different owing to their slightly different diameters. According to my invention the cylinders 5 and 6 rotate at the same angular speed since the pitch line of their respective gears are equal, thereby causing both cylinders to make one revolution in exactly the same period of time, but due to the different diameters of the bodies of the cylinders, the surface of the cylinder 5 runs faster than the surface of the cylinder 6. This causes a slight slip between the bodies of these cylinders 5 and 6 which reduces the length of the print since the impression surface that runs slower than the blanket surface reduces the length of the print approximately equal to the difference in the respective circumferences of the two cylinders.

Interposed between the several printing-couples or units A, B, C and D are three transfer cylinders 13, 14 and 15, the gears of such transfer cylinders being twice the diameter of the gears of the impression-cylinders 6 in the four units to drive same in the directions shown by the arrows, but the peripheries of these transfer cylinders do not travel exactly at the same speed, since the

impression cylinders are slightly less than one-half the diameter of the transfer cylinders. Each transfer cylinder 13, 14 and 15 is provided with two sets of oppositely-disposed grippers 16 and 17 to carry the successive sheets S through the several units. The heavy line P indicates the path of the sheets through the press, and the delivery chains 18 with the grippers 19 passing around the delivery drum 20 take the sheets S printed in four colors from the impression-cylinder 6 of the printing-couple D to the delivery table (not shown). Since the gearing on the cylinders 4, 5 and 6 in each unit A, B, C and D all have the same number of teeth and the gears of the transfer cylinders 13, 14 and 15 have exactly twice as many teeth, the cylinders 4, 5 and 6 make two revolutions in exactly the same time as the transfer cylinders 13, 14 and 15 are making a single revolution.

20 The press is driven from the motor 21 by the belt or chain 22 passing around the pulley 23 and through a train of gears 24, 25 and 26 to the transfer-cylinder 14.

According to my invention, the impression-cylinder 6 of the printing unit D is of standard size while the diameters of the cylinders 6 of the units C, B and A are progressively diminished backwardly through the press to the first unit A, the impression-cylinder 6 of which unit A having the smallest diameter. For example, I have found that where impression-cylinder 6 of the last unit D is ground to 18 inches diameter, the desired equalization of the lengths of the prints on the sheets S may be attained by grinding the diameter of cylinder 6 of unit C to 17.996 inches, with the diameter of cylinder 6 in unit B ground to 17.992 inches, and that of cylinder 6 in unit A ground to 17.988 inches. This difference (4/1000th of an inch) for the varying units 40 is not essential, and these figures are given only by way of example to show how the several impression-cylinders 6 may be ground in graduated relation to each other in the multi-color units to equalize the lengths of the prints on the sheets 45 S as they receive their successive colors, because the edges of the cylinders in the several units are maintained in proper relation and because of the difference in speeds between the printing surfaces of the impression cylinders 6 and the surfaces of the blanket cylinders 5 as hereinbefore described.

Referring to Figs. 2 and 3 the sheet S is shown with the gripper edge on the left and the front line of the print marked L. Where the impression-cylinders 6 of the four units A, B, C and D are of like diameter without over-packing or under-packing the plate cylinders 4 to any appreciable extent, the varying lengths of the prints in the several colors in the units A, B, C 60 and D are shown in Fig. 2 and are designated respectively A', B', C' and D', such variations being due largely to the stretching and swelling of the paper caused by moisture imparted to the plate-cylinders 4 from the dampeners 8.

65 Fig. 3, however, shows the sheet S with the back edges (A', B', C' and D') of the prints in several colors all in registering superposition when the impression-cylinders 6 are ground to varying diameters as hereinbefore described to 70 embody my improvements.

75 My invention in its broadest aspects is not limited to the particular constructions shown, as many changes may be made without departing from the principles of the invention embodying an improved multi-color printing press

in which the impression cylinders are ground in graduated relation to one another so as to equalize the length of the prints of the several colors on the sheet and thereby obtain accurate registry.

I claim as my invention:—

1. A rotary printing-press comprising a series of printing units, the impression-cylinder of each preceding unit having a smaller diameter than its contacting cylinder and the impression-cylinder 10 in the successive unit.

2. A rotary printing-press comprising a series of printing units, the impression-cylinder of each preceding unit being of progressively smaller diameter than its respective contacting cylinder 15 and the impression-cylinder in the successive unit.

20 3. A rotary off-set printing-press comprising a series of printing units having impression, transfer and plate cylinders, each of the impression-cylinders having a different diameter relatively to the others.

25 4. A rotary printing-press comprising a series of printing units having impression-cylinders, each of said cylinders having a different diameter and its impression surface travelling at a speed different from the others.

30 5. A rotary printing-press comprising a series of printing units having impression-cylinders, the diameters of said cylinders being progressively different through the press with the surface of the impression-cylinder of each preceding unit having a lesser surface speed than its coating cylinder.

35 6. A rotary printing-press comprising a series of printing units having impression-cylinders, the diameters of said cylinders in each successive unit being relatively larger forwardly through the press with the surface of the impression-cylinder of each preceding unit having a lesser 40 surface speed than its coating cylinder.

45 7. A rotary printing-press comprising a series of printing units having impression-cylinders, the diameters of said cylinders in each successive unit being in equal graduated relation and progressively larger forwardly through the press with the surface of the impression-cylinder of each preceding unit having a lesser surface speed than its coating cylinder.

50 8. A rotary printing-press comprising a series of printing units having coating cylinders including impression-cylinders, each of said impression-cylinders having a different diameter and the respective impression surfaces of said cylinders travelling at different speeds.

55 9. A rotary printing-press comprising a series of printing units having coating cylinders including impression-cylinders, each of said impression-cylinders having a different diameter and the respective impression surfaces of said cylinders travelling at different speeds, and means for actuating said cylinders.

60 10. A rotary printing-press comprising a series of printing units having impression-cylinders, each of said cylinders having a different diameter 65 but rotating at the same angular velocity.

65 11. A rotary printing-press comprising a series of printing units having coating cylinders including an impression-cylinder, the impression-cylinder of each preceding unit having a smaller 70 diameter than its coating cylinder but travelling at the same angular speed therewith.

75 12. A rotary printing-press comprising a series of printing units each having an impression-cylinder and a contacting cylinder so arranged that

the ratios of the diameter of the impression-cylinder to the diameter of its contacting cylinder are progressively smaller in each preceding unit.

13. A rotary printing-press comprising a series of printing units each having an impression-cylinder and a contacting cylinder so arranged that the diameter of each preceding impression cylinder is less than the diameter of its contacting cylinder by a progressively increasing difference.

14. A rotary printing-press comprising a series of printing units each having an impression-cylinder and a contacting cylinder so arranged that the diameter of the impression-cylinder in each unit is smaller than the diameter of its contacting cylinder by a difference greater than the relative differences in the succeeding units.

15. A rotary printing-press comprising a series of printing units having impression cylinders of different diameters, the respective diameters of which are relatively larger in each successive unit forwardly through the press to compensate for changes in the length of the impression-receiving material passing through the press.

16. A rotary printing-press comprising a series of printing units having impression-cylinders of different diameters, the respective diameters of which are relatively larger in each successive unit forwardly through the press whereby the ratio of the length of the printed impression to the length of the corresponding form is progressively smaller in each preceding unit.
